UNITED STATES PATENT OFFICE.

JOHN M. FREEMAN, OF HICKORY, NORTH CAROLINA.

FILLING-GRADE-CLEARING MEANS FOR LOOMS.

1,406,840.

Specification of Letters Patent. Patented Feb. 14, 1922.

Application filed October 17, 1921. Serial No. 508,176.

To all whom it may concern:

Be it known that I, JOHN M. FREEMAN, a citizen of the United States, residing at Hickory, in the county of Catawba and 5 State of North Carolina, have invented new and useful Improvements in Filling-Grade-Clearing Means for Looms, of which the following is a specification.

The object of my said invention is the 10 provision of sufficient means for keeping the filling grate of a loom perfectly clean in order to enable the fork to be instantly effective when there is no filling between it and the grate, this in order to avert thin 15 places in cloth as when the filling grate is choked with lint or waste or threads so that the filling motion will work as if all of the organized mechanism was in proper working condition. Manifestly my im- 20 provement characterized as indicated will save the labor necessary to the manual cleaning of a filling grate and will also ob- viate the necessity of stopping a loom for such cleaning.

25 To the attainment of the foregoing, the invention consists in the improvement as hereinafter described and definitely claimed.

In the accompanying drawings, forming part of this specification:—

30 Figure 1 is a vertical section of so much of a loom as is necessary to illustrate the application of my improvement.

Figure 2 is a detail perspective showing the improvement and the loom parts adja- 35 cent thereto.

Figure 3 is a section through the attach- ment.

Similar numerals of reference designate corresponding parts in all of the views of 40 the drawings.

The loom illustrated includes the usual frame arch 1, a brake wheel 2, an oscillatory lay 3, and a filling motion including the usual means for driving the motion, a 45 filling grate 4, and a filling fork 5 as well as the usual loop or hook 6 behind the fork. When filling is absent from the path of the fork when the fork approaches the grate, the fork will dwell, and the loop or hook

50 6 will engage the filling motion and cause it to operate for the changing of the filling or the stopping of the loom. My improve- ment is designed to avert choking of the filling grate and to maintain said grate at

55 all times in a clean condition so that the

fork will act promptly when there is no filling between the fork and the grate. The said improvement among other elements includes a rotary brush made up of a head 7 and tufts 8 of long and soft and flexible 60 bristles. The said head 7 of the brush is appropriately fixed on a spindle 9, and the brush is so arranged relatively to the filling grate 4 as to assure the filling grate moving into contact with the bristles of the 65 brush at the back center position of the lay 3 incident to the back and forth movements of the lay. The spindle 9 is arranged to turn in a long tubular bearing 10, and the said spindle 9 may be driven or located 70 from any desired working part of the loom without affecting my claimed invention. For example I may provide the spindle 9 at the opposite end of the bearing 10, with reference to the brush, with a pulley 11 and 75 may connect said pulley by a belt, Figure 1, with a pulley on the shaft of wheel 2, so that in the illustrated embodiment of my invention the rotary brush derives motion from the said shaft of wheel 2. The tubular bearing 10 is disposed in a sleeve 12 on a bracket 13, and a set screw 14 is employed in the said sleeve 12 to adjustably fix the tubular bearing 10 in the sleeve so that the brush can be accurately positioned 80 relatively to the filling grate 4.

The bracket 13 in the present and preferred embodiment of my invention is bolted or otherwise fixed, preferably in adjustable manner, to the frame arch of the 90 loom.

In the practical and successful use of my invention which has been reduced to actual practice, the rotary brush has demonstrated with its efficiency in the cleaning of a filling 95 grate, and experience has also demonstrated that the brush will serve the purpose stated in the dampest places in a weave room or in any place where a loom can be successfully operated, with the result that better 100 production is assured.

It will also be apparent from the fore- going that the same is susceptible of ready application to a loom.

I have entered into a detailed description 105 of the construction and relative arrangement of parts embraced in the present and preferred embodiment of my invention in order to impart a full, clear and exact understanding of the said embodiment. I do 110

not desire, however, to be understood as confining myself to the said specific construction and relative arrangement of parts inasmuch as in the future practice of the 5 invention various changes and modifications may be made such as fall within the scope of my invention as defined in my appended claims.

Having described my invention, what I 10 claim and desire to secure by Letters-Patent, is:—

1. The combination in a loom filling-grate cleaning device, of a rotary brush, means to rotate the brush, and a filling motion including a filling grate arranged to contact with the brush on movement of the lay of the loom.

2. The combination in a loom filling-grate cleaning device, of a rotary brush, means to 20 rotate the brush, and a filling motion including a filling grate arranged to contact with the brush on movement of the lay of the loom; the said brush including a body and tufts of radial bristles on the body.

25 3. The combination in a loom filling-grate cleaning device, of a rotary brush, means to

rotate the brush, and a filling motion including a filling grate arranged to contact with the brush on movement of the lay of the loom; and said brush comprising a body 30 and tufts of radial bristles carried thereby, and the brush being fixed on a rotary spindle, and the spindle being journaled in a tubular bearing adjustably fixed in a bracket on the loom frame.

35

4. A loom filling-grate cleaning attachment comprising a bracket, a spindle carried thereby, a brush fixed on the said spindle, and a drive element for the spindle fixed thereto.

40

5. The combination in a loom filling-grate cleaning attachment of a bracket with a sleeve, a tubular bearing disposed and adjustable in the sleeve of the bracket, means to adjustably fix said tubular bearing in 45 said sleeve, a spindle journaled in the sleeve, a brush fixed to the spindle at one end of the sleeve, and a rotary driving element fixed to the spindle at the opposite end of the sleeve.

50

In testimony whereof I affix my signature.
JOHN M. FREEMAN.
